United States Patent Office

Des. 211,588
Patented July 2, 1968

211,588

CHILD'S CLIMBING APPARATUS OR SIMILAR ARTICLE

Ronald W. Zick, Torrance, Calif., assignor to Jamison,
Inc., Torrance, Calif., a corporation of California

Filed May 1, 1967, Ser. No. 6,903

Term of patent 14 years

(Cl. D34—5)

FIG. 1.

FIG. 2.

FIG. 3.

FIG. 4.

FIGURE 1 is a side elevational view of a child's climbing apparatus or similar article, illustrating my new design;

FIGURE 2 is a top plan view of a child's climbing apparatus or similar article, illustrating my new design;

FIGURE 3 is a front elevational view of a child's climbing apparatus or similar article, illustrating my new design; and

FIGURE 4 is a rear elevational view of a child's climbing apparatus or similar article, illustrating my new design.

The side opposite that shown in FIGURE 1 is a mirror image thereof.

I claim:

The ornamental design for a child's climbing apparatus or similar article, as shown and described.
